(57) **CLAIM**

The ornamental design for a patient transfer harness, as shown and described.

DESCRIPTION

FIG. 1 is elemental view of a patient transfer harness illustrating the patient transfer harness of the present design when placed on a patient to be transferred;

FIG. 2 is a front elevational view of the patient transfer harness of the present design;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines showing environment in the drawings are included for illustrative purposes only and form no part of the claimed design.
